SIGHTING APPARATUS

Frederick C. Yates, Waterbury, Conn.

Application July 6, 1932, Serial No. 621,121

3 Claims. (Cl. 124—15.5)

This invention relates to amusement apparatus, and more particularly to a target practice device having a bull's-eye target adapted to be moved into the line of sight of a stationary simulated firearm or other projectile throwing weapon.

One object of this invention is to provide a device of the above nature in which a target member is carried on one end of a swinging arm pivotally supported on a transversely slidable frame, said arm and frame being adapted for independent positioning by a suitable mechanism located within easy reach of the marksman.

A further object is to provide a device of the above nature in which the accuracy of aim will be indicated by means of suitable indicia in the direct line of aim of the weapon, becoming visible upon the face of said target when said weapon is discharged.

A further object is to provide a target game of the nature set forth, in which the movable target may be provided with a variety of suitable designs to represent some of the popular competitive games, such as bowling, pool, clock-golf, baseball, etc., by means of which a score relative to the game being played may result, and thus add interest to the target practice game.

A further object is to provide a target game of the above nature which will be simple in construction, inexpensive to manufacture, easy to install and manipulate, capable of great variety, and very interesting to play.

With these and other objects in view, there have been illustrated in the accompanying drawings several forms in which the invention may be conveniently embodied in practice.

In the drawings:

Fig. 1 represents a perspective view of a target booth and gun stand, parts of said booth being broken away to show the interior construction and arrangement.

Fig. 2 is a modified form of target, having fifteen indicated circles arranged with their centers on a circular line surrounding and concentric with the rings of a bull's-eye target, and numbered to represent the balls employed in a game of pool.

Fig. 3 is a longitudinal sectional view through the preferred form of simulated rifle employed in the target practice game.

Fig. 4 is a vertical sectional view through the upper part of the target booth, showing the arrangement of the light box.

Fig. 5 is a fragmentary detail perspective view of one end of the target operating handle bar.

Fig. 6 is a longitudinal sectional view through the same.

Fig. 7 is a detail perspective view of the light-box adjustment bracket shown separately from the target booth.

Fig. 8 is a view similar to Fig. 4, showing a modified form of light-box.

Referring now to the drawings in which like reference numerals denote corresponding parts throughout the several views, the numeral 10 indicates in general a target booth consisting of a cover-hood 11, a back-stop 12 and a base 13. The booth 10 is preferably mounted on a ground frame or platform 14 having an integral forwardly extending arm 15, upon the front end of which is permanently mounted a gun standard 16. This construction assures at all times a direct "bead" or aim of a simulated gun 17 in relation to some point located in the target booth 10 regardless of whether said booth 10 or the gun standard 16 becomes accidentally jarred or moved about.

Gun mechanism

The gun 17, as shown in Fig. 3, is constructed to simulate the usual form of a rifle comprising a tubular barrel 18, a trigger mechanism housing 19, and a gun stock 20. Located underneath the barrel 18, and parallel thereto, is an elongated rod 21, having its rear end riveted to the trigger housing and its front end supported by a hanger block 22 attached to the underside of said barrel 18. Slidably supported upon the rod 21 is a tubular handle 23 having fixedly encased therein a sleeve bushing 24, said handle being free to move axially upon said rod 21. The handle 23 is adapted to be manually retracted against the thrust of a helical compression spring 25 surrounding the rod 21 and abutted between the trigger housing 19 and said handle 23.

In order to cock the gun 17 before "firing", the rear end of the handle 23 is provided with an upright catch lug 26 which, as shown in Fig. 3, may preferably be formed integral with the sleeve bushing 24, and is adapted to extend up into the barrel 18 through an elongated slot 27 provided therein. When the handle 23 is retracted, the lug 26 will engage and be restrained by a latch member 28, integral with the forward end of a rocking lever 29, suitably pivoted within the barrel 18. The forward end of said lever 29 is resiliently pressed downward at all times by a leaf spring 30 secured to the upper interior surface of the barrel, as by rivets 31. The rear of the lever 29 extends into the trigger housing 19 and is pro-

80

85

90

95

100

105

110

110

- vided with an integral enlarged head 32 upon its inner extremity.
- For the purpose of tripping the lever 29 and "firing" the gun 17, a trigger 33 is pivotally mounted upon a cross-shaft 34 supported in the trigger housing 19. The trigger 33, having the usual finger grip 35 extending outside the housing 19, is provided with a curved arm 36, to the end of which is integrally secured a hammer head 37.
- 10 The trigger 33 is tensioned by means of a leaf spring 38, the outer free end of which is curved and resiliently pressed up against the underside of the arm 36, while the other end of the spring is held secure by three staggered lugs 39. By 15 means of this construction, when the trigger finger 35 is pulled, the hammer head 37 will strike against the enlarged head 32, causing the lever 29 to trip and release the sliding handle 23, which under the thrust of the compression spring 25, 20 will rapidly slide in a forward direction on the rod 21 to its position as shown in Fig. 3.
- If desired, the gun 17 may be given a more natural effect of realism by having a slight explosion occur when the trigger is pulled. This 25 may be accomplished by means of a hammer 40 secured to the forward end of the sliding handle 23 and adapted to extend upwardly into the barrel through the slot 27. When the handle 23 is released by the action of the trigger 33, the hammer 40 will strike against an explosive cap 41, such as used in toy pistols. The cap 41 is held in an inclined position in the slotted head 42 of a tubular shell 43, detachably fitted into the muzzle end of the barrel 18, and said cap may be dropped into its 30 exploding position through a beveled slot 44 provided in the upper part of the barrel 18 in co-operating alinement with said slotted head 42. Blank cartridges or gongs may also be used for the above purpose.
- 35 40 The exploding position of the cap 41 is preferably well toward the muzzle end of the gun 17 so that there will be no hazard to the operator from flying products of the explosion.
- In order to provide means for aiming the gun, 45 a fore-sight 45 is detachably mounted at the muzzle end of the barrel 18. The fore-sight comprises a small sighting ball or "bead" 46 integrally formed on the top of a cylindrical shank 47 fitted into the upper part of said barrel 18. The shank 50 50 is provided with a reduced section 48 fitted into the lower part of said barrel 18, and said shank 47 serves to hold the encased tubular shell 43 in place.
- The rear sight 49 is in the form of a small 55 angle member attached to the top of the trigger housing 19, the upright leg of said member having a V or U-shaped sighting slot 50 formed therein, the base of said slot being in alinement with the small bead 46 of the fore-sight 45.
- 60 The gun 17 is adapted to be rigidly supported in a grooved block 51 integral with the top of a vertical post 52, said post being securely imbedded within the gun standard 16 against rotative or other motion, relative to the arm 15 or 65 the platform 14. While the weapon simulated in the foregoing description is shown as a rifle such as ordinarily used in present day target practice, it will readily be understood that similar principles may be applied to a device simulating 70 a crossbow, catapult or any ballistic weapon.

Light box

The gun sight, as shown by the dot-and-dash line 53 in Figs. 1 and 3, is in direct alinement 75 with a small aperture 54 formed in the face 55

of a light box 56, which is supported by means of an adjusting bracket 57 secured to the back-stop 12 by a pair of bolts 58 fitted through elongated slots 59 in said back-stop (see Fig. 4). The light box is provided with a hinged cover or lid 60 having an upwardly inclined arm 61 riveted or otherwise secured to the hinged edge of said lid, and said arm is adapted to extend rearwardly through a slot 62 formed in the back-stop 12. A cord 63 is secured to the extremity of this lever 61 and extends downwardly around a guide pulley 64 and thence forwardly through an opening 65 and in an upwardly inclined direction to the forward end of the sliding handle 23. The cord 63 may be fastened to said handle 23 by means of a small lug 66 depending from and integral with the hammer 40, as shown in Fig. 3.

Any suitable lighting means such as an incandescent lamp 67 may be mounted within the box 56. The light emanating from said lamp may be generally diffused around the upper section of the box 56 by means of a curved reflector member 68 suitably mounted therein. The aperture 54 is adapted to be opened and closed by a shutter 69 slidably mounted upon the rear side 100 of the light-box face 55. The shutter is provided with an orifice 70 which, aligning at a predetermined time with the aperture 54, allows a spot of light to pass through said aperture.

In order to interrupt the light spot, the shutter 105 69 is adapted to be vertically raised in a guide frame 71 by a short cord 72, one end of which is connected to the upper part of said shutter, while the other end is attached to the underside of the lid 60, as for example by the small screw-eye 73. 110 The cord 72 is preferably guided over a small rod 74 spanning the upper part of the box 56, so that only a vertical pull may be exerted upon the shutter 69.

In order to properly align the box 56 so that 115 the aperture 54 will lie directly in line of the gun-sight 53, the adjusting bracket 57 is provided with an integral forwardly extending supporting base 75, upon which said box 56 is supported. The supporting base is formed with an elongated center slot 76 and a pair of upright end ribs 77 and 78. Threadedly engaged within said ribs is a pair of transverse set screws 79 and 80 having their inner ends abutted against the side walls of the box 56.

Obviously from this construction the light box 56 may be horizontally adjusted in either direction transversely to the line of sight by the proper manipulation of said set screws 79 and 80. When so adjusted, the light box 56 may be locked in adjusted position by means of a bolt 81 attached to the base of said light box and slidably fitted through the elongated slot 76.

For the purpose of vertically adjusting the light box 56, the lower end of the adjusting 135 bracket has a lateral lug 82 integral therewith, against the underside of which is abutted the end of a set screw 83. The set screw 83 is vertically threaded within another lug 84 integral with the back stop 12, and by manipulating said screw 83 the light box may be adjusted to the required vertical position. The adjustment of the light box 56 so that the aperture 54 falls exactly on the line of the gun sight 53 may be readily checked by removing the fore-sight 45 and passing a string or cord from the sighting slot 50 to the aperture 54.

In order to utilize the light source 67 for illuminating the booth 10 and the front of a target 87 when taking aim, the front of the 130

hood 11 is provided with a downwardly inclined cowl 85, the underside of which may be provided with a reflecting mirror 86, so that when the cover lid 60 is open, the rays of light from the bulb 67 and the reflector 68 will fall upon the mirror 86 and be diffused throughout the booth. If desired, a coin slot 86a may be provided for controlling mechanism, not shown, which will automatically shut off the source of light behind the target after a predetermined number of "shots" have been taken.

Movable target

The movable target member 87, carried on the end of a swinging lever 88, is adapted to pass across the face 55 of the light box 56. The target member comprises an annular metal retaining rim 89 having stretched thereon and clamped, cemented or otherwise attached thereto, a target diaphragm 87a with the usual form of zoned bull's-eye or other suitable design imprinted thereon. The diaphragm is preferably made of a translucent material, such as thin fabric, parchment or oiled paper, which render visible from the front a spot of light directed upon the rearward surface thereof.

The target lever 88 is pivotally fulcrumed upon a pivot stud 90 carried at the upper end of an upright standard 91 (see Fig. 1), integral with a base plate 92 which is adapted to be slidably mounted upon a pair of transversely disposed guide rods 93 and 94. The ends of said rods are supported in a pair of ribs 95 and 96 formed integral with the base 13. An adjustable bifurcated guide member 97 serves to take up side play in the target arm 88 and to maintain the target member 87 in close proximity to the face 55 of the light box 56.

Horizontal movement of the target 87 in either direction transversely to the line of sight 53 is effected by means of a pair of horizontal bars 100 and 101 having their inner ends diametrically joined to a common hub 102. As shown in Fig. 6 the hub 102 is pivotally journaled on a vertical axis to the supporting post 52 and rests upon a shouldered boss 103 formed integral with said post. The free end of the bar 101, as viewed in Fig. 1, is provided with a lug 104 to which is attached a cord 105.

The cord 105 is led toward the booth 10 and guided around a suitable pulley 106 and connected to one side of the sliding base plate 92. The rod 100 has a detachable handle ball 107 provided with a depending lug 108 to which is attached a corresponding cord 109. This cord is led toward the booth 10 and guided around a suitable pulley 110 and connected to the base plate 92 on the side opposite to the cord 105.

Vertical movement of the target 87 is accomplished by means of an additional cord 111 guided around a pulley 112 pivotally attached to the base plate 92. One end of this cord 111 is attached to the target lever 88, and the other end is led to the lower extremity of a vertical swinging arm 113 dependent from and attached to a horizontal sleeve 114 rotatable on the bar 100. The arm 113 is adapted to be manually operated by means of a depending handle 115, preferably made integral with the outer end of said sleeve member 114.

In order to resist vertical displacement of the target due to its weight, there is provided a locking mechanism shown in detail in Figs. 5 and 6. A sector block 116, rigidly secured upon the reduced threaded extremity 100a of the bar 100 by

means of the handle ball 107, provides an engaging surface for a brake shoe 117 attached to an arcuate brake block 118. The brake shoe 117 is adapted to be normally held in tight frictional releasable contact with the periphery of the sector block 116.

For the purpose of releasing the braking mechanism for operating the vertical sighting handle 115, the brake block is connected to the upper end of a releasing handle 119, suitably fulcrumed to a small lateral lug 120 integral with the sleeve member 114. The lower end of the releasing handle is provided with a knurled curved gripping section 121, which is adapted to extend downwardly in close proximity to the handle 115. The underside of the section 121 has a strong leaf spring 122 riveted thereto and resiliently pressed against said handle 115 for normally exerting outward pressure upon said section 121, thus clamping the brake shoe 117 to the sector block 116. The brake is readily released by manually pressing the handle section 121 toward the handle 115 against the force of the spring member 122 during the sighting operation.

Operation

In the operation of the target practice apparatus, the operator will first cock the gun by pulling back on the handle 23 until it latches. This causes the booth 10 and the front surface of the target to be illuminated and the light within the box to be cut off from the aperture 54. The operator will then move the target 87 in front of the box 56 by the manipulation of the ball handle 107 and the depending handle 115, the object of the game being to position the center of the bull's-eye target in direct alinement with the line of sight 53. With the target adjusted according to the best of his ability, the operator will then pull the trigger 35, simultaneously causing the blank cap 41 to be exploded, the light in the booth to be extinguished, and a concentrated point of light to appear on the surface of the translucent target diaphragm to indicate the accuracy of the "shot".

Fig. 2 illustrates a modified design of target face which may be substituted for the zoned bull's-eye shown in Fig. 1, in order to add interest to the target practice. The target face 123 is similar to the target diaphragm 87a, except that the bull's-eye 124 imprinted upon the translucent surface is reduced in size and is surrounded by a series of minor or secondary targets in the form of concentric circles 126 symmetrically disposed with their centers lying on a circle concentric with the circle forming the bull's-eye. The outer circles 126 represent the balls as used in the game of pool, and the ball numbers are designated by numerals 127 numbered from "1" to "15" and disposed in irregular sequence around the target, as clearly shown in Fig. 2. The circles 126 representing the balls will be preferably colored according to the regulation pool table set in order to render conspicuous the bull's-eye of the ball and the spot to be aimed at for scoring. It will be apparent from this arrangement that a score may result similar to that of "shooting" pool. It will also be apparent that the target arrangement may be so constructed as to represent other popular games, such as bowling, clock golf, baseball, etc.

In the modified form of light-box shown in Fig. 8 the construction is in many respects similar to that shown in Fig. 4 except for the lighting system to be hereinafter explained. The light box 56 is provided with a removable cover lid 128

instead of the hinged cover lid 60 as in Fig. 4. A single light bulb 129 is secured within the box in direct alinement with the aperture 54 by means of a socket 130. A concave reflector 131 5 may be disposed behind the bulb 129 in such a position as to cause an intense light to shine through the aperture 54.

The booth 10 and exterior of the light box in the modified form may be illuminated by means 10 of a single bulb or preferably a group of bulbs 132 suitably spaced beneath the cowl 85 of the hood 11.

The incandescent lamps 129 and 132 are adapted 15 to be alternatively energized through a double-throw switch mechanism 133 located on a panel 134 attached to the rear of the back-stop 12. The switch mechanism 133 comprises a pair of stationary contact members 135 and 136 and a movable contact member 137 adapted to be oscillated between said stationary contacts for 20 alternatively completing the circuits through the lights 129 and 132 by electric conductors 138 and 139 respectively. The movable contact 137 is carried upon the end of a switch lever 140 25 and is connected to one side of an electric power supply by a conductor 141. This lever is pivotally attached to the panel 134 and adapted to be oscillated throughout its range of travel by the cord 63 which is connected to the mechanism 30 of the rifle 17 in a manner explained above, the tension of the cord being opposed by a spring 142 fixed at one end to the panel 134 and disposed in a manner clearly shown in Fig. 8. The arrangement of electrical circuits connecting one 35 side of the power source through the double-throw switch and its respective contacts and the lamps 129 and 132 to the other side of the power source is clearly shown in Fig. 8. It is obvious from this construction and arrangement that 40 when the gun 17 is cocked by retracting the handle 23, the light 129 in the box 56 will be extinguished and the light group 132 energized. When the gun is discharged, the alternative condition is brought about, the external lights 132 45 being extinguished and the lamp 129 within the box illuminated, producing a concentrated light through the translucent target from the rear locating the line of sight and indicating the accuracy of the aim.

If desired, the platform 14 may be placed on 50 an adjustable table or other support for permitting the use of the apparatus in a standing position. Moreover, the gun standard 16 may be mounted separately from the remainder of the apparatus.

As shown in Figs. 4 and 8, the hood 11 is formed 55 with an upward inverted U-shaped section 145 for permitting the target 87 to be swung in a greater arc than usual, if it is found necessary

due to the location of the light box 56 or the size of the target.

While there have been disclosed in this specification several forms in which the invention may be embodied it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a target practice game apparatus, the combination of a stationary weapon simulating member, a booth fixed relatively thereto and containing a light box and a movable target, said light box having an aperture in alinement with the sights of said weapon simulating member, a light source adapted to illuminate said aperture from the rear, an alternative light source adapted to illuminate said booth and the face of said target, means for positioning said target both 100 vertically and horizontally in juxtaposition to the face of said light box between said weapon simulating member and said aperture, indicia upon said target adapted to be made conspicuous by illumination from said aperture, thus furnishing 105 an indication of the operator's marksmanship.

2. In a target practice game apparatus, the combination with a stationary sighting instrument, a movable translucent target, means for positioning said target horizontally under the 110 control of the operator, a light box having an aperture in line with the sight of said sighting instrument, a normally ineffective source of concentrated illumination upon the rear face of said box, and means to render said source of concentrated illumination effective after the instrument 115 has been aimed, thus furnishing an indication of the operator's skill.

3. In a target practice game apparatus, the combination of a stationary weapon simulating 120 member, a booth fixed relatively thereto and containing a light box and a movable target, said light box having an aperture in alinement with the sights of said weapon simulating member, a light source adapted to illuminate said aperture 125 from the rear, means for positioning said target both vertically and horizontally in juxtaposition to the face of said light box between said weapon simulating member and said aperture, indicia upon said target adapted to be made conspicuous 130 by illumination from said aperture, thus furnishing an indication of the operator's marksmanship.
